UNITED STATES PATENT OFFICE.

CHRISTIAN BERGH BACKER, OF NEW YORK, N. Y.

TERMINAL FOR ELECTRIC HEATING UNITS.

Application filed July 30, 1927. Serial No. 209,424.

My invention relates to tubular electric heaters and particularly to terminal structures therefor.

An object of my invention is to provide a relatively simple terminal structure for a tubular heater that shall embody means co-operating with the casing for preventing turning and longitudinal movement of an electric-insulating bushing constituting a part 10 of the terminal structure.

Another object of my invention is to provide a terminal structure for a tubular heater that shall embody means to ensure that no longitudinal pull or stress on the terminal 15 lead shall be transmitted to the resistor.

A further object of my invention is to provide a terminal structure for an elongated tubular heater that shall permit of fully assembling the terminal structure in the tubular heater before treating the assembly with a high-pressure and high-temperature oxidizing agent.

My invention is particularly applicable to encased tubular heaters comprising a tubular 25 metal casing, a helical resistor wire located therein and held tightly by a mass of initially metallic magnesium hydroxide. The terminal structure proper embodies a bushing of electric insulating material having a coaxial 30 opening extending partially therethrough and communicating with a plurality of angularly extending openings extending through the other portion of the bushing. The outer portion of the bushing extending beyond the 35 end of the tubular casing is made substantially square in lateral section to permit of peripherally spaced portions of the end of the casing being bent downwardly against the flat surfaces. A doubly bent conductor 40 wire is looped around a portion of the plug or bushing extending through certain of the angularly extending openings and through the coaxial opening and is twisted with an extending end of the resistor wire to provide 45 a terminal lead.

In the drawings, Figure 1 is a view, in side elevation, of one form of tubular heater comprising the device embodying my invention,

Fig. 2 is an enlarged view in longitudinal section through an end portion thereof, 50

Fig. 3 is a view of the device shown in Fig. 2 looking from left to right,

Fig. 4 is a view in lateral section taken on the line IV—IV of Fig. 2,

Fig. 5 is a plan view of a terminal insulating bushing looking in the direction of the 55 arrows on line V—V of Fig. 2, and

Fig. 6 is a view, in longitudinal section, through a bushing of electric-insulating material embodying my invention taken on the 60 lines VI—VI of Fig. 5.

The terminal structure embodying my invention is particularly applicable to a tubular electric heater of the type shown generally in Fig. 1, designated by 11, and embodying 65 an outer metal casing 12, a helically wound resistor wire 13 located therein and held tightly by a mass 14 of initially metallic magnesium hydroxide and oxide extending peripherally of the helix 13.

The method of production of the mass 14 of magnesium hydroxide is more particularly disclosed and claimed in my Reissue Patent No. 16,340. Briefly, the method comprises the location of an open helix of resistor wire, 75 such as the helix 13, in a tubular casing such as the casing 12, an open helix of a magnesium strip being located therebetween. Upon subjection of the assembled structure to the action of high-pressure and high-temperature 80 steam or water for a predetermined length of time, the initially metallic magnesium is changed into a crystalline mass of magnesium hydroxide or oxide, which mass has a much greater volume than that of the magnesium 85 helix or member. The mass 14 is a crystalline mass of magnesium hydroxide or oxide which not only holds the helix of resistor wire tightly within the casing, but provides also a heat-conducting path of low thermal resistance between the wire and the tubular casing.

One of the requirements of complete transformation of the initially metallic magnesium to magnesium oxide is that the high-temperature 95 and high-pressure oxidizing agent shall

have continuous free access to all portions of the tubular casing and more particularly to the initially metallic magnesium, in order that all of the metallic magnesium shall be 5 changed to magnesium hydroxide.

A plug or bushing 15, of electric-insulating material, such as steatite, porcelain or other suitable material, has an inner portion of such shape in lateral section, as to fit closely within 10 an end portion of the casing 12, a shoulder portion 16 being provided in the inner surface of the tube, if desired, in order to limit the inward movement of the plug 15.

The outer portion of the plug 15 is substantially square in lateral section, and may be provided with rounded corners.

The outer half length of the plug 15 is provided with an axial opening 17 which is in communication with a plurality of angularly 20 extending openings 18, 19, 20 and 21 located within the inner half portion of the plug 15. The opening 17 is slightly larger than are the openings 18 to 21, inclusive. As shown in the drawing, the openings 18 to 21, 25 inclusive, communicate with the inner end of the opening 17 and those portions of the plug at the junction point are preferably rounded over as shown more particularly in Figs. 2 and 6.

30 One end of the resistor wire 13 may extend through the opening 20 and through the opening 17 and therebeyond a sufficient distance to provide part of a terminal lead for the device. A looped piece of resistor wire 35 22 is pushed through openings 18 and 19 and the opening 17, after which it is twisted with the end of the resistor 13 extending through the opening 20 and the main opening 17 to provide a substantially flexible terminal lead 40 having a current-carrying capacity larger than that of the resistor wire itself, in order to ensure that the terminal structure will operate at a relatively low temperature.

The inner faces or surfaces of the plug located 45 radially inwardly from the openings 18 to 21 may also be rounded so that the loop 22 may be twisted tightly, as shown in Fig. 2 of the drawing, with the outer end of the resistor wire 13. A structure of this kind 50 precludes the transmission of any longitudinal pull on the terminal lead to the resistor helix 13 itself.

As hereinbefore noted, I provide four angularly extending openings in the inner half portion of the plug or bushing 15, and use only three of these to receive the looped wire 22 and the resistor wire 13. This leaves the opening 21 free and unobstructed, whereby the entrance of the high temperature and 60 high pressure oxidizing fluid required for transforming the initially metallic magnesium into magnesium hydroxide, is freely permitted. It is thus possible to completely assemble the terminal plug, and the looped 65 wire thereon in the end of the casing and

bend spaced portions thereof over the squared end of the plug, before subjecting it to the heat treatment. This overcomes the necessity for any further work being done on the terminal structure or the heating unit 70 after it has thus been treated.

It is obvious that, while I have shown four radially extending openings in the inner portion of the plug 15, I may use a larger number in accordance with the number of looped 75 terminal lead wires, which I may desire to use.

Various modifications may be made in the device embodying my invention without departing from the spirit and scope thereof, 80 and I desire that only such limitations shall be placed thereon as are imposed by the prior art or are set forth in the appended claims.

I claim as my invention:

1. In a terminal structure for a tubular heater comprising a tubular casing and a resistor therein, in combination, a plug of electric-insulating material insertable into the end of said casing, said plug having a 90 coaxial opening extending partially therethrough, a plurality of angularly extending openings extending through the other portion of the plug and intersecting with said coaxial opening, one end of the resistor being 95 inserted through one of the angularly-extending openings and the coaxial opening, and a pair of said angularly extending openings, and a terminal lead looped through said coaxial opening and twisted with the end of 100 the said resistor.

2. In a terminal structure for a tubular heater comprising a metal casing and a resistor wire insulatedly mounted therein, in combination, a plug of electric-insulating material in the end of said casing having an opening therethrough of Y-shape, and a terminal lead wire extending through said opening and looped around a portion of the plug and twisted with one end of the resistor 110 wire.

3. In a terminal structure for a tubular heater comprising a metal casing and a resistor wire insulatedly mounted within the casing, in combination, a plug of electric-insulating material in the end of the casing, projecting therefrom and having an opening of Y-shape extending longitudinally therethrough, and a doubled-over terminal lead located in and extending from said plug, 115 looped around a portion thereof and twisted with an end of the resistor wire.

4. In a terminal structure for tubular or sheathed electric-resistor heaters, in combination, a bushing of insulating material adapted to fit into the ends of the tube or sheath, said bushing being provided with a longitudinally extending opening through which the resistor extends from the inside of the tube or sheath to the outside thereof, and 125 130

a plurality of spaced openings extending through the bushing at an angle to its longitudinal axis and intersecting said longitudinally extending opening, and a conductor 5 looped through said spaced openings and adapted to be twisted around said resistor whereby said resistor may be anchored to the bushing when the bushing has been positioned in the end of the tube or sheath.

10 5. A support and insulating bushing for tubular or sheathed electric-resistor heaters to which the resistor may be anchored and by means of which the terminal of the resistor

is insulated from the tube or sheath, said support and bushing comprising a block of 15 insulating material provided with a longitudinally extending opening and a plurality of spaced openings beginning from one end of the bushing and extending at an angle to the longitudinally extending opening and intersecting the same at a point near its other end.

In testimony whereof, I have hereunto subscribed my name this 22nd day of July, 1927.

CHRISTIAN BERGH BACKER.
